PNEUMATICALLY ACTUATED PUMPING
SYSTEM

Charles A. Butler, Okmulgee, Okla.

Application March 31, 1932. Serial No. 602,349

12 Claims. (Cl. 103—246)

This invention relates to improvements in systems for pneumatic pumping, and is more particularly directed to such systems as may be employed for pumping liquids from great depths, 5 as from oil wells and the like, as described in my co-pending applications Serial No. 401,788, filed October 23, 1929 and Serial No. 602,348 filed March 31, 1932.

A feature of the present invention is the provision of means whereby a greater effective pneumatic pressure is employed upon the valve actuating devices than is employed in the pumping cylinder itself.

Another feature of the present invention is the provision of means for reducing the back pressure against the exhaust of air from the pumping cylinder.

A further feature of the invention is the provision of similar means for reducing the back pressure upon the exhaust from the control valve actuator when the level of liquid in the well is above the particular cylinder.

Other features of the invention reside in particular constructions of the parts, and such as appear in the following specifications and claims.

An illustrative form of embodiment of the invention is set forth on the accompanying drawings, in which:

Figure 1 is a view, substantially in vertical axial section of a well pipe, showing the connection of a plurality of pumping units.

Fig. 2 is a vertical section through the upper end of one of the units substantially on line 2—2 of Fig. 6 and including also the exhaust pipe connections thereto.

Fig. 3 is a vertical diametral section, substantially on line 3—3 of Fig. 6, showing the portion of the unit just below that shown in Fig. 2.

Fig. 3a is a detail view, in section, of the actuating piston and cylinder and its valve.

Fig. 4 is a similar view, showing the portion just beneath that shown in Fig. 3.

Fig. 5 is a side elevation, on the scale of Fig. 2, showing the ascending pipe connections from each unit.

Fig. 6 is a top plan view of an upper closing plug, showing the location of the apertures for the several pipe connections.

In this illustrated form of the invention the well casing C is of the usual type and is located in the well hole in the usual manner, and is provided above the ground with a casing head H.

An air pressure line 10 is provided, which passes from the ground downwardly to the last pumping unit. In Fig. 1, two pumping units P,

Pa are shown which are connected in series or cascade in a manner hereinafter described, whereby the lower unit receives liquid from the well and delivers it to the upper unit which in turn delivers the liquid to the outlet pipe 11. The lower unit P receives the liquid through a strainer connection 12 located at the bottom of the well.

The air pipe 10 is shown as passing downward through an intermediate pumping unit, and is provided above each unit with a branch connection for delivering air to each unit. For this purpose, the sections of pipe 10 are threaded into a branch connection piece 116 (Figs. 2 and

5) which has a lateral passage leading into a chamber through which passes a tube 13, which at its lower end is threaded into a valve housing 125, and the latter in turn is threaded into the upper head 18 of the pumping unit. The pumping unit includes the casing 19 which is threaded at top and bottom and is provided with

an upper coupling 20 and a lower coupling 21 which are respectively threaded to the upper closing plug 18 and the lower closing plug 22 whereby the parts of the pumping unit may be easily dismounted for inspection and repair.

The upper closing plug 18 is provided with a passage 26 through which air may be exhausted from a particular unit while it is being filled with oil. This plug 18 also has a connection for the oil delivery pipe 27 leading to the next upper unit or to the outlet pipe 11. Brackets 28 are provided from point to point to support the pipes 10

and 27 and the exhaust pipes 59a and 26a.

Threaded in the lower end of the exhaust aperture 26 is a slotted valve sleeve or cage member 30 having a sliding plunger 31 therein, at the upper end of which is mounted an exhaust closing valve 32 adapted to seat itself against the valve seat flange 33 of the sleeve 30. At the lower end of the sleeve 30, it is threaded into the casing 34 of the piston valve-controlling mechanism.

This casing provides a cylinder 35 in which may reciprocate the piston 36 which has a piston rod 37 connected by a pivot 38 to a lever 39 having a rounded head 40 serving as a

pivot for support in a lateral cavity of the support arm 41 which in turn is supported in the lower end of the inlet valve casing or cage 43. This inlet valve casing 43 likewise contains an inlet valve plunger 44 which has mounted at its upper end the inlet valve 45 which is adapted to be seated against the valve seat flange 46 of the casing 43.

The lower end of the cylinder 35 is closed by a plug 47 having a packing 48 and a gland nut 49 to seal the piston rod 37. In the

60

65

70

75

80

85

90

100

105

110

upper portion of the casing 34 is provided a bore hole 50 in which is rockably seated the valve body 51 having an externally projecting stem 51a upon which is mounted the lever 52 having a downwardly projecting arm 52a. This lever arm 52a is connected by a pivot 100 to a swinging link 101 which is guided at its lower end in an aperture in shelf 102 rigid with the casing 34. A spring 103 surrounds the link 101. Stop pins 104 are provided on casing 34 to limit the oscillating movement of the lever 52, 52a. The lever 52 is joined by the link 53 to the straps 53a which support the pivot 54a of the lever 54. The oscillating valve body 51 moves opposite the valve ports 55, 56, 57 in the casing 34, so that a cavity 58 in the bottom of the valve body 51 may alternately establish communication between the port 55 and the port 57 with the central port 56, which is connected by a conduit 59 with a passage 135 in the upper head 18, a suitable gland 136 being provided to assure tightness. Above the head 18 an extension pipe 59a is carried to a point, say 100 feet, above the plug 18 and is provided, at its upper end, with a valve housing 137a having therein a valve 137 which may be opened by exhausting air moving upwardly in pipe 59a, and which closes when the air pressure within and without the pipe 59a are substantially balanced. Thus, the discharge of air from the central port 56 through conduits 59, 59a is independent of the position of valve 33. At the same time that the valve body 51 by its cavity 58 establishes communication between the outlet port 56 and either port 55 or 57, the space surrounding the valve body 51 is brought into communication with the other port 57 or 55, so that air may pass from the pipe 13 into the nipple piece 130 and thus downward in pipe 61, through the plug 18, to the port 62 and thus to the space around the valve body 51 and into such other port. The upper end of pipe 61 is packed in the nipple piece 130 by a suitable gland 131; glands 133, 134 are provided at the upper and lower surfaces of the plug 18 to prevent leakage through the plug along the passage 132 surrounding the tube 61.

The lever 39 has a pivot 63 by which it is connected to the pull rod 65 having a pivot connection 66 at its upper end to the operator member 67 whose ends project through slots to the inlet and outlet valve casings 43 and 30 and are received in the cavities of the respective inlet and outlet valve plungers 44 and 31. The lever 54 is pivotally connected to and supported by a rod 68 which is threaded into the upper closing plug 18. The free end of the lever 54 projects over the float 71. The straps 53a are connected by a link 53b to the lower operating lever 69 which is mounted by a pivot 70 on a rod 72 supported on a lower stirrup 73 which connects the pipe 78 with a pipe 10 within the casing 19. The end of lever 69 extends beneath the bucket 74 which is located within a shield 75 having an aperture 76 at the lower end thereof and being supported by a bracket 77 secured to the pipes 78 and 10. A similar bracket 77 is provided at the upper end of the shield 75, to which is connected a spring 82 which extends downward in the bucket 74 and is connected to the bottom thereof. Figure 4 also shows the provision of a bracket 81 for supporting a bottom stop 81a upon which the float 71 may rest, when in its lowermost position.

At the lower end of the outlet or discharge conduit 78 is mounted a valve chamber 83 having a valve seat 84 thereon to receive the valve 85 which is guided by valve supports 86 which engage

the stem of this valve. The lower end of the valve casing 83 is open to the interior of the casing 19 of this pump unit.

The air pressure line 10 is passed through the packed aperture 87 in the lower closing plug 22. The lower closing plug 22 is likewise provided with an aperture 90 into the lower end of which is threaded the liquid pipe which, it will be understood, corresponds either to the section strainer 12 or the delivery line 27 in Figure 1, accordingly as the unit is located at the bottom or an intermediate point along the casing C. A bushing 92 is threaded into the upper end of the casing 90 and receives the valve cage 93 of the ball foot valve 94.

The float 71 is illustrated as constructed in the manner described in my aforesaid co-pending application, Serial No. 602,348, filed March 31, 1932, to which reference may be made for details thereof.

From the exhaust passage 26 in the upper plug 18 (Fig. 5) leads a pipe 26a which, like pipe 59a, is preferably extended a considerable distance above the particular pumping unit, as for example 100 feet, and is provided thereat with a valve housing 137b containing a valve 137c which opens when the pressure within the exhaust pipe 26a exceeds the pressure prevailing in the well casing, and closes when the pressures reach a substantial balance.

The valve housing 125 in the upper plug 18 is provided with a nipple piece 130, and has within it the guide 138 for the stem of a valve 126 which seats itself against the lower surface of the valve housing 125, and is held normally in closed position by a spring 127 whose effect may be regulated by an adjusting nut 129. Normally, the spring tension may be kept at such a point that the valve will only open when the pressure within the branch air pipe 13 is of the order of fifty pounds greater than the pressure within the pumping cylinder.

In the form shown in the drawing, the branch air tube 13 is extended through the connection 116, and the latter is packed with respect thereto by the pack gland 119 at the lower end of this branch connection 116. Surrounding the portion of the tube 13 which extends above the branch connection is a threaded bushing 124 which at its upper end has a further packing 120 for preventing the escape of air from the air line. The upper end of pipe 13 is closed by a cap 121. The branch air pipe 13 is provided with apertures 122 at the point of the enlarged passage 117 within the branch connection so that air may flow freely from the air line 10 into the branch air pipe 13. Surrounding these apertures, within the passage 117, is a screen 123 intended to retain any rust or scale, present in the pipe 10, from access to the pumping system. This screen may be removed by separating the bushing 124 from the branch connection 116. By this arrangement, the air pressure within the branch pipe 13 is transmitted to the cap 121, and operates in tension on the pipe 13 itself, so that no reaction strain is thus imposed upon the connection 116 and the main air line 10.

The operation of such a pumping unit is controlled by the presence of the liquid therein, and hence a description of the operation of one unit will suffice as an indication of the operation of successive units in chain which are operating under identical circumstances.

Assuming that the particular unit is immersed in liquid, as for example when the well has been

standing, or there is so great a flow of liquid thereinto that a high level is reached, and that the pumping unit is substantially free of liquid, the successive phases of operation are as follows:

5 Since the unit is empty of liquid, the bucket 74 and the float 71 are in their lower positions. The valve body 51 has just moved to its extreme 80
10 counterclockwise position and space 50 is in communication with port 55, and port 56 is in communication with port 57. The piston 36 is in raised position, the exhaust valve 32 is closed, and the inlet valve 45 is open.

Air from the air pipe 10 passes to the branch pipe 13 and is yet being admitted past the spring 15
15 valve 126 and the inlet valve 45 to the interior of the pump cylinder. The movement of valve 51 which has just been accomplished by the bucket 74, under the assumptions made, has established communication so that air may now 20
20 flow from the nipple piece 130 by conduit 61 to space 50 and thus to the upper end of the cylinder 35, while the space at the lower end of the cylinder is permitted to exhaust through the pipe 57a and port 57, port 56 and pipes 59, 59a 25
25 and the valve 137 to a point where the static liquid pressure in the well is say fifty pounds less 30
30 per square inch than at the pumping unit itself. Hence an energetic movement of the piston 36 is occasioned which closes the inlet valve 45 and opens the exhaust valve 32. The air pressure 35
35 in pipe 10, however, is continued upon the piston 36. The piston 36 moves downward and rocks lever 39 so that the pull rod 65 causes a reversal of the position of the inlet valve 45 and the exhaust valve 32. The admission of air from 40
40 pipe 10 into the casing 19 is shut off, and the air in this casing is now permitted to exhaust into passage 26, and by pipe 26a and valve 137c is discharged into the well at a point where the static liquid pressure is say fifty pounds less than at the pumping cylinder.

Owing to this static pressure of the liquid in the well, the liquid passes through the strainer 12 into the interior of the cylinder and serves 45
45 to expel this air, if the unit be located at the bottom of the well, or operates by reducing the lifting heads in lower units, so that liquid enters if it be located as an intermediate or upper unit in a chain. This entering liquid passes the 50
50 foot valve 94 and rises in the unit. As it rises along the length of the bucket 74 the latter is raised by spring 82 and the lower lever 69 is thus freed. Ultimately, the liquid raises the float 71 and actuates the lever 54 and therefore 55
55 reverses the valve 51, the arm 52a and link 103 cooperating by means of spring 101, by a toggle action to move the valve quickly and definitely to its end position.

The valve body 51 is now in its clockwise-moved position, and air from the branch air pipe 13 may pass through conduit 61 to space 50 and thus to port 57 and by pipe 57a to the lower end of cylinder 35. Exhaust occurs from the upper end of cylinder 35 through port 55, port 56 and pipes 59, 59a, and again to a point where the static liquid pressure is less than at the particular unit. The piston 36 moves upward and therewith closes the exhaust valve 32 and opens the inlet valve 45, this operation occurring easily since the pressure within the cylinder corresponds to a static liquid pressure which in the illustrated case is fifty pounds less than that prevailing at the cylinder, and the first movement of the valve 45 establishes communication from the interior of the pumping unit to

the valve 126 which is exposed to substantially the pressure differential corresponding to the seating of spring 127, i. e. although the pressure in pipe 10 may be 200 pounds per square inch, yet by exhausting the air from pipe 26a at a point 100 feet higher than the unit (i. e. a pressure difference of approximately fifty pounds per square inch), the admission of air past valve 126 at a pressure of 150 pounds per square inch is yet fifty pounds greater than the pressure of liquid outside of the unit: or an effective pressure, with respect to the liquid if for example the unit be at the bottom of the well, of 200 pounds per square inch.

The entering air operates as a pneumatic piston upon the liquid contained within the pumping unit to expel it past the valve 85 into the pipe 78 and thus to the next upper unit or to the discharge pipe 11. As the liquid level drops, the float 71 is permitted to seat itself upon a buffer 81a of bracket 81: and finally the bucket 74, by reason of its weight owing to the presence of liquid therein, descends and actuates the lever 69 to again reverse the position of the valve body 51.

The parts are now returned to the first assumed position, and the action is continued so long as the air is supplied into pipe line 10 and liquid is drawn from the well and discharged from pipe 11.

The aforesaid connection of the exhaust lines 59 and 26 to the extension pipes 59a and 26a is of particular advantage when the level is higher than two of the pumps, as air pressure differences are thereby established, in conjunction with the spring valve 126 which permits the continued operation of the system without the passage of air into a lower unit, through the outlet valve 85 thereof, giving rise to the establishment of a column of air and liquid within the connecting pipe 27, and ultimately producing a very volatile and inflammable mixture at the casing head of an oil well, and also liable to foam and cause damage when admitted into the next higher unit. Although this difficulty usually arises only when the column of liquid in the well casing is substantially at the same height as one of the units, yet it is found that the present structure operates quietly and efficiently under all levels of liquid existing in the well. It will particularly 110
110 be noted that the valves 137 and 137c are seated by their weight, in the particular example, and by the weight of any liquid thereabove, so that a quantity of oil is not permitted to escape downward in the pipes 59a and 26a.

It is obvious that the invention is not limited solely to the form of construction shown and described, but that various modifications may be made therein, without departing from the scope of the appended claims.

Having thus described the invention, what I claim as new and desire to secure by Letters Patent, is:

1. In a pneumatically actuated pump adapted to be immersed in the liquid in a well, a casing, a compressed fluid line, a liquid line opening into the casing adjacent its bottom and extending upwardly from the casing, an exhaust line extending upwardly from the casing and open at a point in the well liquid above the casing so that the back pressure in the exhaust line is less than the liquid pressure around the casing, a valve for closing the exhaust line adjacent its upper end, valve means for alternately opening communication between said casing and air line and between

- said casing and exhaust line, a liquid admission conduit opening into the casing and a valve for closing the same, pneumatically actuated means for moving said valve means, and means controlled by the liquid level in said casing for alternately establishing communication between said liquid line and said pneumatically actuated means and for exhausting said pneumatically actuated means.
10. 2. A pump as in claim 1 including an automatic pressure reducing valve between said fluid line and the casing, and in which said pneumatically actuated means is placed by said controlled means directly in communication with said fluid lines independently of said pressure reducing valve.
15. 3. A pump as in claim 1, including means whereby the pneumatically actuated means exhausts to a point above the casing whereby a differential between the hydrostatic pressure existing in the liquid at the casing and at the exhaust discharge point assures the actuation of said pneumatically actuated means.
20. 4. In a pneumatically actuated pump, a casing having an upper head, a compressed fluid line extending through the casing and assisting in supporting the same, a branch piece on said fluid line, a branch air tube extending from said upper head through said branch piece and closed with respect thereto and closed at its upper end, said tube having ports in its walls within said branch connection so that fluid may pass from the fluid line into said branch tube, whereby fluid pressure within said branch tube is transmitted solely to said tube and does not produce a reaction upon said branch piece.
25. 5. A pneumatically actuated pump system comprising a plurality of vertically spaced pumping units, and valved conduits for connecting the same in cascade, in which at least two lower units may be submerged in a liquid to be pumped, a compressed fluid line, a branch connection from each unit to said fluid line, each of said submerged units including a pressure retaining valve located in said branch connection thereof, an exhaust pipe extending from the unit to a point thereabove where the hydrostatic pressure is lower when the unit is submerged, valve means for alternately placing the casing in communication with the fluid pressure branch connection and with the exhaust pipe, and means controlled by the liquid level in said casing for moving said valve means.
30. 6. In a pneumatically actuated pump for operation in a well, a casing, a compressed fluid line and a liquid delivery line mechanically connected to the pump whereby to support the same, said liquid delivery line communicating with the interior of the casing adjacent its bottom, a liquid admission conduit opening into the casing and a valve for closing the same, a branch tap on said compressed fluid line, a pipe extending through said tap and communicating at one end with the interior of said casing and being closed at its opposite end and communicating at said tap with said compressed fluid line whereby balanced axial pressures in said pipe relieve the compressed fluid line of strain therefrom, and devices controlled by the liquid level in said casing for controlling the flow of fluid from said pipe into said casing and release of fluid from the interior to the exterior of said casing.
35. 7. In a pneumatically actuated pump, a casing having upper and lower heads, a compressed air line connected to the upper head, a liquid delivery line passing through the upper head and opening into the casing adjacent its bottom, an inlet valve to admit air from said air line into said casing, an exhaust valve to permit the escape of air from said casing, a liquid admission conduit opening into the casing and a valve for closing the same, a double acting piston and cylinder assembly, means actuated by said piston to move said inlet and exhaust valves, a valve for controlling the passage of air from said air line selectively to the ends of said cylinder and from said cylinder to the outside of the casing, means operated by high and low levels of liquid in said casing to operate said control valve and including a lever arm, and a spring to move said arm toward its end positions and in which power is stored when said arm is moved from an end position.
40. 8. In a pneumatically actuated pump, a casing having upper and lower heads, a compressed air line connected to the upper head, a liquid delivery line passing through the upper head and opening into the casing adjacent its bottom, an inlet valve to admit air from said air line into said casing, an exhaust valve to permit the escape of air from said casing, a liquid admission conduit opening into the casing and a valve for closing the same, means including an air pressure operated device for actuating said inlet and exhaust valves, a valve for controlling the admission of air to and release of air from said air line operated means, means including a link for moving said control valve, a float and a bucket for moving said link in opposite directions and operated according to the liquid level in said casing, and a suspension spring supported in said casing at its upper end and extending downward in said bucket and connected at its lower end to said bucket for balancing the weight thereof when said casing contains liquid at a level above the upper end of said bucket.
45. 9. In a pneumatically actuated pump, a casing having upper and lower heads, a compressed air line connected to the upper head, a liquid delivery line passing through the upper head and opening into the casing adjacent its bottom, an inlet valve to admit air from said air line into said casing, an exhaust valve to permit the escape of air from said casing, a liquid admission conduit opening into the casing and a valve for closing the same, means including an air pressure operated device for actuating said inlet and exhaust valves, a valve for controlling the admission of air to and release of air from said air line operated means, a lever for operating said control valve, a link pivotally connected to said lever and extending downward in said casing, upper and lower levers mounted on fixed pivots within said casing and pivotally connected to said link, a float for rocking the upper lever upwardly when a predetermined upper liquid level has been established in said casing, and a weighted bucket for rocking said lower lever downwardly when a predetermined lower liquid level has been produced in said casing, whereby said link is moved in opposite directions by said float and said bucket.
50. 10. In a pneumatically actuated pump, a casing having upper and lower heads, a compressed air line connected to the upper head, a liquid delivery line passing through the upper head and opening into the casing adjacent its bottom, an inlet valve to admit air from said air line into said casing, an exhaust valve to permit the escape of air from said casing, a liquid admission conduit opening into the casing and a valve for closing the same, means including an air pressure operated device for actuating said inlet and exhaust valves, a valve for controlling the admission of air to and release of air from said air line operated means, a lever for operating said control valve, a link pivotally connected to said lever and extending downward in said casing, upper and lower levers mounted on fixed pivots within said casing and pivotally connected to said link, a float for rocking the upper lever upwardly when a predetermined upper liquid level has been established in said casing, and a weighted bucket for rocking said lower lever downwardly when a predetermined lower liquid level has been produced in said casing, whereby said link is moved in opposite directions by said float and said bucket.

- closing the same, means including an air pressure operated device for actuating said inlet and exhaust valves, a valve for controlling the admission of air to and release of air from said air operated means, a lever connected to said control valve to move the same, stop devices to limit the movement of said lever, a link pivotally connected to said lever and spring means engaging said link for urging said lever from central toward its 10 end positions, one said stop limiting the movement of the lever in one direction from central position to a first end position to a less distance than the movement of the lever to its other end position, a float and a weight in said casing and 15 means whereby said float and weight move said lever in opposite directions, the float serving to move the lever from the first end position.
11. In a pneumatically actuated pump, a casing, a compressed air line, a liquid delivery line 20 opening into the casing adjacent its bottom, an inlet valve to admit air from said air line into said casing, an exhaust valve to permit the escape of air from said casing, a liquid admission conduit opening into the casing and a valve for closing the same, means including an air-pressure 25 operated device for actuating said inlet and exhaust valves, valve means for controlling the admission of air to and release of air from said air 30

- operated means selectively as it occupies end positions, means operated in accordance with the liquid level in said casing for moving said valve means, and devices for rapidly moving said valve means from central to one end position when said means has been moved by said liquid level means away from the other end position. 80
12. In a pneumatically actuated pump, a casing, a compressed air line, a liquid delivery line opening into the casing adjacent its bottom, an inlet valve to admit air from said air line into said casing, an exhaust valve to permit the escape of air from said casing, a liquid admission conduit opening into the casing and a valve for closing the same, means including an air-pressure operated device for actuating said inlet and exhaust valves, valve means for controlling the admission of air to and release of air from said air 85
